NOVELTY FOOTWEAR

Dee Burston Bass, Bronx, N. Y., assignor to Heirloom Needlework Guild, Inc., New York, N. Y., a corporation of New York

Application February 1, 1939, Serial No. 253,976

3 Claims. (Cl. 36—45)

This invention relates to novelty footwear and has particular reference to ladies' boudoir slippers such as scuffs, mules and the like which include an upper having an inner ply secured to the sole, a relatively separable ornamental outer ply and an inwardly directed edge portion secured to the inner ply and overlying the same to form a recess therewith in which recess the 5 edge portions of the outer ply are adapted to be inserted for retaining the outer ply in covering relation with the inner ply.

The invention further provides a novelty footwear in which the outer ply is relatively separable from the upper for facilitating the application of ornamentation thereto and whereby the outer ply may be cut to the shape or contour dictated by the design of the shoe and associated with the shoe during the building of the 10 same, then separated therefrom for the application of ornamentation thereto and thereafter inserted in position in the upper.

The invention further comprehends an article of footwear of the indicated character in which the outer ply is constructed of an open mesh fabric and is relatively separable from the upper for applying needle work ornamentation thereto and when completed the outer ply is retained in position by disposing its edges beneath the inwardly directed overlying edge portions of the 15 upper.

The invention is further directed to novelty footwear of the indicated character which are to be sold in partially completed condition and which are so constructed and arranged as to permit of the separation of the outer ply of the upper from the inner ply thereof to facilitate completion of the same by hand needlework, such as petit-point, needle-point or embroidery 20 stitches extending through the outer ply and when so completed the replacement of said plies in superimposed assembled relation with each other.

With these and other objects in view, the invention is set forth in greater detail in the following specification and illustrated in the accompanying drawings in which:

Fig. 1 is a perspective of a lady's slipper constructed in accordance with the invention and illustrating the outer ply of the upper which 25 is adapted to be ornamented in its assembled superimposed relation to the inner ply.

Fig. 2 is an enlarged fragmentary sectional view taken approximately on the line 2—2 of Fig. 1.

Fig. 3 is an enlarged transverse sectional view taken approximately on the line 3—3 of Fig. 1, illustrating the inner ply of the upper separated from the outer ply to facilitate the application of the ornamentation to said outer ply.

Fig. 4 is a collective perspective view of a mod-

ified form of the invention illustrating a slipper with a separable insert adapted to receive ornamentation separated from the upper to facilitate the application of ornamentation thereto.

Fig. 5 is an enlarged fragmentary sectional view taken approximately on the line 5—5 of Fig. 4, illustrating the insert in assembled relation with the slipper.

Fig. 6 is a perspective view of a further modification illustrating the upper ply portions which are adapted to be ornamented in separated relation to the inner ply of the upper.

Fig. 7 is a perspective view illustrating the ornamented upper ply in assembled superimposed covering relation to the inner ply of the upper.

Fig. 8 is an enlarged transverse sectional view taken approximately on the line 8—8 of Fig. 7.

Fig. 9 is an enlarged fragmentary longitudinal sectional view taken approximately on the line 9—9 of Fig. 7.

Referring to the drawings by characters of reference and more particularly to the form of the invention illustrated in Figs. 1, 2 and 3 of the drawings, the slipper or scuff includes a sole 10 and an upper including inner and outer plies 11 and 12 which are secured together along their marginal side edges and attached to the sole 10 in any suitable manner, such as by binding strips 13. The outer ply 12 preferably is 15 constructed of open mesh fabric to serve as a foundation material for the application thereto of ornamentation, such as needle-point and embroidery stitches and which may be stamped or printed with a design pattern as a guide for facilitating the application of the ornamentation 20 thereto.

In order to facilitate the application of the ornamentation to the outer ply 12, the same is unsecured with reference to the inner ply excepting at the side edges thereof so that the plies 25 11 and 12 may be relatively separated or spaced apart as illustrated in Fig. 3. After the ornamentation has been applied thereto, the plies are re-arranged with the outer ply in superimposed covering relation with the inner ply and this relation is maintained by means of rim portions or strips 14 carried by the unsecured marginal or free edges of the inner ply and extend inwardly therefrom into overlying relationship with the inner ply so as to define a marginal recess or 30 channel 15 therewith into which the free marginal edge portions of the outer ply 12 are tucked or inserted for retaining the outer 35 ply in superimposed covering relation with the inner ply.

In order to normally hold the rim portions or strips 14 in overlying relationship with the inner 40 ply 11, the opposite ends thereof are secured together with the plies to the sole of the shoe by the binding strips 13. While the rim portions or 45

+ strips 14 inherently assume the overlying relationship to the inner ply of the upper, they are capable of being flexed to an opened position for facilitating the insertion of the edge portions of 5 the outer ply 12 within the recesses or channels 15.

In the modified form of the invention illustrated in Figs. 4 and 5 of the drawings, the inner ply 20 of the upper together with a continuous 10 rim portion 21, are secured to each other throughout their outer marginal edges and the lower marginal edge portions are attached to the sole 22 from adjacent the shank and around the forepart leaving the inner continuous marginal 15 edge 23 of the rim portion 21 free from the inner ply 20 to provide a continuous marginal recess or channel 24. In this form, the outer ply 25 is in the form of an insert which is constructed of an open mesh fabric to serve as a foundation for 20 the ornamentation and which outer ply or insert 25, after being ornamented, is associated with the inner ply 20 by positioning the marginal edge portions between the inner ply 20 and the rim 21 so that the outer ply or insert is retained within 25 the recess 24 and disposed in superimposed covering relation to the inner ply 20. Under this construction and arrangement, a plurality of outer plies or inserts 25 bearing different ornamentation may be interchangeably associated 30 with the slipper.

In the form of the invention illustrated in Figs. 6 to 9 inclusive, of the drawings, the inner ply of the upper includes oppositely disposed mating sections 30 and 31 secured together by stitching 35 32 or other securing means along their confronting inner edges, the outer ply likewise consisting of similarly fashioned oppositely disposed mating sections 33 and 34 which are secured along their side edges to the side edges of the sections 40 of the inner ply and to and between the outer and inner soles 35 and 36 of the slipper.

The sections 33 and 34 of the outer ply are unsecured with reference to the inner ply and the sole of the slipper excepting along the side edges 45 thereof as hereinbefore described, so as to permit of relative separation of the said sections as illustrated in Fig. 6 to facilitate the application of ornamentation thereto. The sections of the outer ply are preferably fashioned from open 50 mesh fabric for receiving ornamental needlework covering the upper surface thereof as illustrated in Fig. 7 and when thus ornamented the confronting inner edges of the sections are secured together by stitching 37 and the free edge 55 portions of the outer ply are inserted under the inwardly directed rim portions 38 which are secured to the free upper edges of the inner ply and extend inwardly therefrom to provide a recess therewith. The free edges of the sections 60 33 and 34 forming the outer ply thus being retained in the said recess, secure the outer ply in superimposed covering relation with the inner ply.

It will be apparent from the foregoing that a 65 novelty footwear is produced which may be ornamented as desired by the purchaser and which is so constructed that the outer ply may be relatively separated from the remainder of the upper so as to facilitate the application of the ornamentation thereto and when ornamented the 70 upper ply may be readily inserted and retained in superimposed covering relation with the inner ply.

What is claimed is:

1. In an article of footwear having a sole and an upper, said upper including an inner ply secured to the sole, an inwardly directed rim member secured to the inner ply along an edge of said rim and extending into overlying relationship with said inner ply and said rim being free from securement to said inner ply along its other edge to define together with said inner ply an open recess, and an outer ply of mesh fabric adapted for needlework ornamentation and disposed in covering relation to the inner play with an edge portion extending into said recess, said outer ply being relatively separable from the inner ply for providing a working space between said plies by means of which said needlework may be applied to the outer ply for ornamenting the same, said outer ply when ornamented, being adapted to be redisposed in covering relation with the inner ply and to have its edge portion positioned in said recess for retaining the same in said covering relation with the inner ply.

2. In an article of footwear having a sole and an upper, said upper including an inner ply secured to the sole, an inwardly directed rim member secured to the inner ply along an edge of said rim and extending into overlying relationship with said inner ply and said rim being free from securement to said inner ply along its other edge to define together with said inner ply an open recess, and an outer ply of flexible mesh fabric adapted for needlework ornamentation and secured at its opposite side edges to the sole and disposed intermediate its side edges in covering relation to the inner ply with an edge portion 35 extending into said recess, said outer ply being relatively separable from the inner ply by withdrawing said edge portion from the said recess and by depressing the inner ply so that a working space is provided between said plies for the application of said ornamental needlework to the outer 40 ply and said outer ply when ornamented being adapted to be redisposed in covering relation with the inner ply and to have its edge portion positioned in said recess for retaining the same in 45 said covering relation with the inner ply.

3. In an article of footwear having a sole and an upper, said upper including an inner ply secured to the sole, an inwardly directed rim member secured to the inner ply along an edge thereof and extending into overlying relationship with said inner ply to define together therewith a recess, and an outer ply including mating sections each secured at one edge to the sole and being free at the other edge and being adapted 55 to have the adjacent free edges thereof secured together and disposed in covering relation to the inner ply with an edge portion of said outer ply extending into said recess and said sections being relatively separable from the inner ply so that a working space is provided between said plies during the application of ornamental needlework thereto and said outer ply after being 60 ornamented and after having the adjacent free edges of the sections secured together being 65 adapted to be redisposed in covering relation to the inner ply and to have the edge portion positioned in said recess for retaining the same in covering relation with the inner ply.
